HAND DRILL

Frank B. Lewandowski, Detroit, Mich.

Application February 7, 1946, Serial No. 646,014

6 Claims. (Cl. 123—195)

1

This invention relates to improvements in hand drills.

The primary object of this invention is the provision of a self-contained unitary hand drill which is compact, efficient in use and relatively cheap to manufacture.

Other objects and advantages of this invention will be apparent during the course of the following detailed description.

In the accompanying drawings, forming a part of this specification, and wherein similar reference character designate corresponding parts throughout the several views—

Figure 1 is a vertical cross sectional view taken longitudinally through the improved hand drill, showing the associated parts thereof.

Figure 2 is a plan view of the improved hand drill.

Figures 3^a and 3^b are views showing a timer arrangement and associated with the hand drill.

Figure 4 is a front end view of the hand drill.

Figure 5 is a rear end view of the hand drill.

Figure 6 is a diagrammatic view showing the wiring diagram.

In the drawings, wherein for the purpose of illustration is shown only a preferred embodiment of the invention, the letter A may generally designate the improved hand drill. It includes a casing structure B supporting a boring tool arrangement C. A gas engine construction D is associated in a compact relation with the casing B having a drive connection E with the boring tool C. A timer F is provided for regulating the supply of current to a spark plug G of the engine, and a carburetor H to be associated in an out of the way and compact relation with respect to the casing structure.

The casing structure is of a nature to provide a hand grip of a somewhat conventional type found upon portable hand drills. This casing structure includes a main body portion 10 having integrally formed therewith a handle 11; the space between the body 10 and handle 11, designated at 12, being adapted to receive the fingers of the user. Of course the hand portion 11 is of tubular formation. The casing structure in the lower half of the body portion 10 is provided with a compartment 14 which continues over the base 15 of the casing structure and at 16 continues upwardly for approximately half the vertical height of the hand grasping portion 11, which is of tubular formation. This compartment arrangement is adapted to receive gasoline or a liquid fuel supply, and the compartment is closed at the sections 14 and 16 by means of pump walls

2

14^a and 16^a. The latter supports a conduit 17 which extends upwardly through the upper half of the hand grasping portion 11 and is laterally extended to the right at the top of the tubular hand grasping portion; terminating in a removable cap 20 exteriorly of the casing. This, of course, is a filling cap and the tube 17 is used to pour the fuel into the above mentioned compartment arrangement. The remainder of the 10 casing structure includes an upper portion 21 which is integral with the above mentioned compartment providing lower construction of the casing, and associated in a complementary relation with the portion 21 is a removable cover section 22 which encloses the entire upper half of the casing structure and forms a part of the latter for enclosing compartments which contain such items as a drilling tool arrangement, batteries, coils and feed line 17, as will be apparent 15 from the drawings.

The cover section 22 is secured by means of removable screws 23 to the other part of the upper casing structure, as will be noted from the drawings. The drilling tool arrangement C consists of

25 a shaft 30 rotatably journaled at 31 in a bearing supported between the complementary parts of the upper housing structure 21 and the closure 22. In normal position the shaft 30 is horizontal and supports a chuck 32 at its outer end for receiving a drilling bit 33. At its inner end the shaft 30 bears upon a flange or web 34 which is integral with the housing structure 21, and between this and the bearing 31 the shaft 30 is provided with a gear 35. A countershaft 36 is journaled at 37 upon the housing structure in horizontal parallel position below the shaft 30. The closure section 21 may be provided with casing structure which journals this shaft. A gear 40 meshing with the gear 35 is keyed upon the shaft 36, and 30 this shaft extends forwardly externally of the casing structure and there is provided with a flywheel 42 which may also be in the nature of a fan and pulley wheel for a power takeoff.

Within the casing structure the shaft 36 at its 45 inner end is provided with a crank 45 for connection with the piston rod of the gas engine to be subsequently described.

The gas engine structure D preferably comprises a stationary cylinder 50 which may be 50 secured in any approved manner to the casing B, preferably forwardly thereof and below the closure 22. The cylinder structure may be provided with a bolt or screw arrangement 52^a for supporting the same in position, and at the bottom thereof it supports the spark plug G in the re-

lation shown in Figure 1. The piston 55 slidably operates in the cylinder 50 and it has a piston rod 52 eccentrically mounted with the crank wheel 45, which, of course, forms part of the shaft 36.

In the compartment at the upper part of the casing structure defined by the integral portions 21 and the closure 22, there is placed an induction coil 60 upon a support 61 and thereabove upon a support 62 there are placed batteries 64. Each of them has one contact 65 insulated on the casing structure connected at 66 with the induction coil, and at its opposite end a contact grounded upon the casing at 70.

As shown in Figure 4 the carburetor H is mounted as a part of the casing structure upon the left side of the casing, looking forwardly. The carburetor has suitable adjusting connections 75 and a pipe connection 76 which leads into the lower part of the gasoline compartment, as shown in Figure 1. An exhaust outlet or manifold 78 is provided at the opposite side of the cylinder 50.

The timing structure is provided as a part of the ignition setup consisting of a bracket which is clamped at 81^a upon the bearing or housing portion in which the shaft 36 is journaled. This bracket 80 supports an insulated contact 81 connected by a line 82^a in the ignition system. A resilient member 82 of spring metal has a second contact 83 thereon, grounded in the circuit. The shaft 36 is provided with a cam 87 keyed therewith which upon rotation will cause the contacts 81 and 83 to engage for closing the circuit and sparking the plug once for each revolution of the shaft 36.

The wiring system will be apparent from Figure 6, since the same reference characters appear therein and refer to the parts given like reference characters in the above description.

It will be apparent from the foregoing that a very compact type of self-contained drilling tool has been provided. The operation, of course, will be apparent. A switch designated at 90 in Figure 6 may be placed upon the tool at any desired location. Merely by closing it and flipping the wheel 42 will cause the motor to operate. The crank shaft 36, of course, is geared with the driven shaft 30 and so long as the batteries are good and fuel remains in the casing the tool will operate. The casing structure is preferably of some aluminum alloy, and of course all parts, except the engine cylinder, may be made of light weight materials.

Various changes in the shape, size and arrangement of parts may be made to the form of invention herein shown and described without departing from the spirit of the invention or the scope of the following claims.

I claim:

1. In a hand drill of a self-contained unitary type the combination of a casing structure having a hand grip portion, said casing structure including in the lower part thereof a fuel reservoir extending upwardly into the hand grip portion, filling means carried by the hand grip for filling the reservoir, a driven shaft, an internal combustion engine cylinder carried by the casing structure, and an ignition system for the internal combustion engine structure including a battery, induction coil, spark plug for the engine and timer all operatively connected and carried by the casing structure.

2. In a portable hand drill the combination of a casing structure having a hand grip formed as a part thereof, said casing structure in the lower

part thereof having a reservoir which extends into the hand grip for receiving a liquid fuel, said casing structure in the upper part thereof having a removable complementary closure as a part thereof and together with the casing structure defining an upper compartment, a driven shaft rotatably supported by the upper casing structure, an internal combustion engine cylinder supported by the casing structure forwardly of the hand grip, a piston for the cylinder, a crank shaft rotatably supported by the upper casing structure operatively connected to the piston, means gearing the crank shaft with the driven shaft, a spark plug carried by said cylinder, a timer operatively connected with the crank shaft, a removable induction coil and battery supported in the upper casing compartment, and a carburetor for feeding fuel from said reservoir to the internal combustion engine.

3. In a portable hand tool the combination of a casing structure having a base portion provided with a fuel reservoir, and an upper compartment providing portion, a handle connected with the casing at one side thereof, a driven shaft supported by the upper part of the casing structure on a normal horizontal axis, an internal combustion engine providing means supported by said casing structure for driving said driven shaft including a crank shaft operating on an axis parallel to the driven shaft, operating means connecting the crank shaft with the driven shaft, a cylinder carried by the upper part of the casing structure at the opposite side of the casing structure from the handle, and a piston for said cylinder connected with the crank shaft.

4. In a portable hand tool the combination of a casing structure having a base portion provided with a fuel reservoir, and an upper compartment providing portion, a normal vertically disposed handle connected with the casing at one side thereof, a driven shaft supported by the upper part of the casing structure on a normal horizontal axis, an internal combustion engine providing means supported by said casing structure for driving said driven shaft including a crank shaft operating on an axis parallel to the driven shaft, means connecting the crank shaft with the driven shaft, a cylinder carried by the upper part of the casing structure at the opposite side of the casing structure from the handle, and a piston for said cylinder connected with the crank shaft, said crank shaft having an external power takeoff means facing in the same general direction and adjacent to said driven shaft.

5. In a portable tool the combination of a casing structure including a lower base portion providing a fuel reservoir, a handle carried at a side of the base portion, said casing structure including an upper compartment providing portion extending normal to the line of the handle, a horizontal driven shaft supported by said upper casing portion, piston and cylinder means connected with the casing portion, a crank shaft geared to the driven shaft having operative connection with the piston means, means in the upper compartment providing casing portion providing an ignition system including an induction coil and battery, and means for attaching a work bit to said driven shaft.

6. In a hand operated portable tool the combination of a casing structure comprising a lower base portion having a fuel reservoir therein, and an upper compartment providing portion having a removable closure for access to the compartment thereof, said casing structure including a

normally vertically disposed handle as a part thereof, an internal combustion engine carried by the casing structure directly opposite the handle including a vertically disposed operating piston, a horizontally disposed crank shaft mounted on the casing structure having operating connection with said piston, a vertically disposed tool attaching shaft carried by said casing structure geared to the crank shaft, and means in the upper compartment providing an ignition system for 10 said internal combustion engine.
